UNITED STATES PATENT OFFICE.

ELMER O. BEARDSLEY AND WALTER F. PIPER, OF CHICAGO, ILLINOIS, ASSIGNEES TO THE BEARDSLEY & PIPER COMPANY, OF CHICAGO, ILLINOIS, A CORPORATION OF ILLINOIS.

MOLDING MACHINE.

Application filed December 4, 1922. Serial No. 604,658.

To all whom it may concern:

Be it known that we, ELMER O. BEARDSLEY and WALTER F. PIPER, both of the city of Chicago, in the county of Cook and State 5 of Illinois, United States of America, having invented certain new and useful Improvements in Molding Machines, do hereby declare that the following is a full, clear, and exact description of the same.

The invention relates to molding machines.

In the operation of sand projectors which are movably supported by a pair of arms or jibs, as exemplified in Patent No. 1,309,833 dated July 15, 1919 and Reissue Patent No. 15,292 dated February 28, 1922, it has been found that where the flasks are provided with retaining bars of unusual thickness, the sand is not packed as densely 20 as desired under the bars, because the sand is delivered vertically into the flask.

The object of the present invention is to overcome this objection and to provide a sand projector of the aforesaid type in 25 which provision is made for a slight angling of the line of delivery of the sand when it is necessary, in order to pack the sand under wide retaining bars of flasks. Other objects of the invention will appear from 30 the specification.

The invention consists in the several novel features hereinafter set forth and more particularly defined by claims at the conclusion hereof.

In the drawings: Fig. 1 is a side elevation of a machine embodying the invention, parts being shown in section. Fig. 2 is a perspective of the bracket and hanger for supporting the projector carrying arm. Fig. 3 is 35 a transverse section on line 3—3 of Fig. 1. Fig. 4 is a longitudinal section through the projector and its supporting arm. Fig. 5 is a section on line 5—5 of Fig. 4. Fig. 6 is a transverse section showing the gearing for driving the feed belt from the projector shaft.

The machine illustrated comprises a supporting standard 35, a jib or arm 36 pivoted to the standard to swing horizontally; an 40 arm or jib 37 which is pivotally sustained by the outer end of the jib 36 so as to swing horizontally relatively thereto, a sand projector supported at the outer end of arm 37 and including a casing 38 and a rotor 39 45 provided with a projector and shear blade

40, a shaft 41, to which the rotor is secured, extending through arm 37 and connected to electric motor 42 which is movable with said arm, a vibratory conveyor chute 43 containing a riddle 44 and mounted to swing 50 with jib 36, a case 45 containing mechanism including a motor (not shown) for vibrating chute 43, and an endless belt 46 for feeding sand from the conveyor 43 to the casing 38 of the projector, carried by a 55 drive pulley 47 and an idler pulley 48, both mounted to move horizontally with arm 37. The mechanism for vibrating the chute 43 and the gearing for driving pulley 47 may be of the construction set forth in 60 Patent No. 1,408,493, dated March 7, 1922 to which reference may be made for a more detailed description thereof. The projector shaft 41 extends through the tubular arm 37 and a housing 49 which is fixedly secured to the tube forming the arm 37 and to the motor 42 which is secured to the inner end of said housing. The pulley 47 for driving the sand feeding belt 46 is 65 driven by gearing comprising a pinion 51 in housing 49 and fixed to shaft 41; a gear 52 on a transverse shaft 53; a pinion 54 on shaft 53; an idler 55 meshing with pinion 54 and with a gear 56 fixed to the hub of drive-pulley 47. Pinion 54 and gears 55 and 70 56 are enclosed in a suitable casing 57. Shaft 58 for pulley 47 is mounted in case 57 and an arm 59 fixed to one side of housing 49. An upwardly flared guide-chute 60 is 75 supported over the inner end of belt 46 to direct the sand from the conveyor-chute 43 onto belt 46 in all positions of the arm 37. Chute 60 is secured to guide-bars 70 which are disposed over belt 46 and are supported by rods 71 which are secured to lugs 72 on hanger 80 62 and rod 73 which are suitably secured to arm 37. The connection between the arm 37 and jib 36 comprises a hanger 62 having a seat 85 62' in which tubular arm 37 is rigidly secured by U-bolts 63; a stud 64 disposed above the arm and extending longitudinally of said arm and through hanger 62 so that the hanger will be pivotally sustained from the stud; a bracket 65 rigid with stud 64 and bowed around arm 37 and extending under the housing 49; and a pintle 66 which is rotatably held in bearings in a bracket 67 which is fixed to the outer end of jib 36. The jib 36 and arm 37 and the pivotal con- 90 95 100 105 110

nection between pintle 66 and bearing bracket 67 exemplify a connection which permits the projector, motor and sand-conveyor carried thereby, to be swung horizontally so the projector will sling sand into all portions of the flask while maintaining a substantially constant angle of delivery. Normally, arm 37 is suspended from bracket 65 and stud 64 so that the projector casing 10 will be positioned to cause the sand to be projected vertically downward.

In the filling of flasks with wide retaining-bars, it is desirable to slightly angle the line of delivery to project the wads and 15 pack the sand under the bars or other undercut spaces. The operator can rock the arm 37 around the horizontal axis of stud 64 which is parallel with the axis of the arm 37, and shift arm 37, the projector casing, motor 42, housing 49, belt 46 and chute 60, all of which are mounted on said arm, in unison sufficiently to cause the sand to be projected under the retaining-bars in the 20 flask. This rocking of the projector is accomplished by grasping and shifting the handles 61, on the projector-casing. When the handles are released, the projector and arm 37 will move by gravity to their normal position under stud 64. On account 25 of the preponderance of weight at one side of the arm, caused by the gearing for driving the feed-belt 46 and case 57, arm 37 will normally hang slightly to one side of the vertical plane intersecting the axis of 30 stud 64, and the projector casing is arranged so the wads of sand will be discharged vertically while the arm is so positioned. The sides of chute 60 are flared, as at 69, to catch the sand from chute 43 in all of the 35 positions of arm 37. The hanger 62, by which the arm 37 is suspended, is disposed outwardly from the pintle 66 and at a point where the load will be substantially balanced longitudinally to avoid cramping between 40 stud 64 and hanger 62.

The invention exemplifies a molding machine of the projector type in which the projector is mounted so it can be shifted horizontally to sling wads of sand at high speed 45 and in a substantially constant direction into all portions of the flasks and in which provision is made for rocking the projector to project the wads of sand at a sufficient angle to pack the sand under wide retaining bars 50 in the flask or undercut spaces in the flask or patterns therein. A characteristic of this construction is that the projector is movable bodily and horizontally to sling sand into all portions of the flask without variation 55 of the angle of delivery and that provision is made for sufficiently angling the line of delivery to pack the sand under wide retaining-bars when they are in the flask, to 60 pack the sand under the bars or in other undercut spaces. Another characteristic is 65

that the projector is moved bodily and horizontally to sling sand in a substantially constant, vertical or angular direction, so the operator can move the projector lengthwise of the bars in the flask to direct the projector-casing to sling the sand at a slight but constant angle. Another characteristic is that the operator does not bear any of the weight of the projector or parts carried by arm 37 while in normal operation, because the arm is suspended from the stud 64 and the operator can easily rock the projector for angular delivery whenever occasion therefor arises.

The invention is not to be understood as 70 restricted to the details set forth, since these may be modified within the scope of the appended claims, without departing from the spirit and scope of the invention.

Having thus described the invention, what 75 we claim as new and desire to secure by Letters Patent, is:

1. In a molding machine, the combination 80 of a sand-projector comprising a rotor and a casing, means to support the projector for horizontal bodily movement to sling sand into all portions of the flask at a substantially constant angle of delivery, means for feeding sand to the projector, means for driving the projector, and means for suspending the projector so it can be rocked laterally when desired.

2. In a molding machine, the combination 85 of a sand projector comprising a rotor and a casing, means to support the projector for horizontal bodily movement to sling sand into all portions of the flask at a substantially constant angle of delivery, means for feeding sand to the projector movable with the casing, means for driving the projector, 100 and means for suspending the projector so it can be rocked laterally when desired.

3. In a molding machine, the combination 105 of a sand projector comprising a rotor and a casing, means to support the projector for horizontal bodily movement to sling sand into all portions of the flask at a substantially constant angle of delivery, means for feeding sand to the projector, means for driving the projector, movable with the casing, and means for suspending the projector so it can be rocked laterally when desired.

4. In a molding machine, the combination 110 of a sand projector comprising a rotor and a casing, means to support the projector for horizontal bodily movement to sling sand into all portions of the flask at a substantially constant angle of delivery, means for feeding sand to the projector movable with said casing, means for driving the projector 115 also movable with the casing, and means for suspending the projector so it can be rocked laterally when desired.

5. In a molding machine, the combination 120 of a sand projector comprising a driven 125

- 5 rotor and a casing, a horizontally swinging jib, an arm pivoted to the free end of the jib to swing horizontally and supporting at its free end the projector, means for feeding sand to the projector, and a connection for pivotally supporting the arm to permit the projector to be shifted to incline the angle of delivery when desired.
- 10 6. In a molding machine, the combination of a sand projector comprising a rotor and a casing, a jib pivoted to swing horizontally, an arm pivoted to the free end of the jib to swing horizontally and supporting at its free end the projector, driving mechanism for the rotor movable with the arm, means for feeding sand to the projector, and a suspension connection for the arm which permits it to swing bodily around an axis substantially aligned with the arm.
- 15 7. In a molding machine, the combination of a sand projector comprising a rotor and a casing, a jib pivoted to swing horizontally, an arm pivoted to the free end of the jib to swing horizontally and supporting at its free end the projector, driving mechanism for the rotor movable with the arm, means for feeding sand to the projector, and a connection for pivotally supporting the arm to permit the projector to be shifted to incline the angle of delivery when desired.
- 20 8. In a molding machine, the combination of a sand projector comprising a rotor and a casing, a jib pivoted to swing horizontally, an arm pivoted to the free end of the jib to swing horizontally and supporting at its free end the projector, driving mechanism for the rotor movable with the arm, means for feeding sand to the projector movable with the arm, and a suspension connection for the arm which permits it to swing bodily around an axis substantially aligned with the arm.
- 25 9. In a molding machine, the combination of a bracket pivoted to swing horizontally, a horizontally extending arm pivoted to the bracket, so as to swing laterally therewith and to be capable of transverse bodily pivotal movement, and a sand projector movable with said arm and comprising a rotor and a casing.
- 30 10. In a molding machine, the combination of a bracket pivoted to swing horizontally, a horizontally extending arm pivotally hung from the bracket so as to swing laterally therewith and to be capable of transverse bodily movement, and a sand projector mounted on said arm comprising a rotor and a casing.
- 35 11. In a molding machine, the combination of a bracket pivoted to swing horizontally, a horizontally extending arm pivotally hung from the bracket so as to swing laterally therewith and to be capable of transverse bodily movement, a projector mounted on the arm and comprising a rotor and a casing, sand-feeding mechanism mounted on the arm, and a motor for driving the projector movable with the arm.
- 40 12. In a molding machine, the combination of a sand projector comprising a rotor and a casing, an arm pivoted to move horizontally and supporting at its free end the projector, driving mechanism for the rotor, means for feeding sand to the projector, and a connection which permits the arm to swing bodily around to vary the angle of delivery.
- 45 13. In a molding machine, the combination of a sand projector comprising a rotor and a casing, an arm pivoted to move horizontally and supporting at its free end the projector, driving mechanism for the rotor movable with the arm, means for feeding sand to the projector, and a connection which permits the arm to swing bodily to vary the angle of delivery.
- 50 14. In a molding machine, the combination of a bracket pivoted to swing horizontally, a horizontally extending arm pivoted to the bracket, so as to swing laterally therewith and to be capable of transverse bodily pivotal movement, and a sand projector movable with said arm and comprising a rotor and a casing.
- 55 15. In a molding machine, the combination of a bracket pivoted to swing horizontally, a horizontally extending arm pivotally hung from the bracket so as to swing laterally therewith and to be capable of transverse bodily movement, and a sand projector mounted on the arm comprising a rotor and a casing.
- 60 16. In a molding machine, the combination of a bracket pivoted to swing horizontally, a horizontally extending arm pivotally hung from the bracket so as to swing laterally therewith and to be capable of transverse bodily pivotal movement, a projector mounted on the arm and comprising a rotor and a casing, sand-feeding mechanism mounted on the arm, and a motor for driving the projector movable with the arm.
- 65 17. In a molding machine, the combination of a bracket pivoted to swing horizontally, a horizontally extending arm pivotally hung from the bracket so as to move laterally therewith and capable of transverse bodily pivotal movement, a projector mounted on the arm and comprising a rotor and a casing, sand-feeding mechanism mounted on the arm, and a motor for driving the projector movable with the arm.
- 70 18. In a molding machine, the combination of a bracket pivoted to swing horizontally, a horizontally extending arm, a sand projector at one end of the arm, a motor for driving the projector at the other end of and movable with the arm, and a pivotal

supporting connection between the bracket and the arm disposed intermediate the projector and the motor.

19. In a molding machine, the combination of a jib pivoted to swing horizontally, a bracket pivoted to swing horizontally in the outer end of the jib, an arm, a sand projector at one end of the arm, a motor for driving the projector at the other end of and movable with the arm, and a pivotal supporting connection between the bracket and the arm disposed intermediate the projector and the motor.

20. In a molding machine, the combination of a bracket pivoted to swing horizontally, an arm, a projector at one end of and movable with the arm, a motor for driving the projector at the other end of and movable with the arm, a sand-feeding belt and gearing for driving it from the motor mounted on and movable with the arm, and

a pivotal supporting connection between the bracket and the arm disposed intermediate the projector and the motor.

21. In a molding machine, the combination of a jib pivoted to swing horizontally, a bracket pivoted to swing horizontally in the outer end of the jib, an arm, a projector at one end of and movable in all directions with the arm, a motor for driving the projector at the other end of and movable in all directions with the arm, a sand-feeding belt and gearing for driving it from the motor mounted on and movable in all directions with the arm, and a pivotal supporting connection between the bracket and the arm disposed intermediate the projector and the motor.

Signed at Chicago, Illinois this 17th day of November, 1922.

ELMER O. BEARDSLEY,
WALTER F. PIPER.
